(57) CLAIM

The ornamental design for a bus roof enclosure system, as shown and described.

DESCRIPTION

FIG. 1 is a front perspective view of a bus roof enclosure system in accordance with the present invention.

FIG. 2 is a side elevational view of the bus roof enclosure system of FIG. 1.

FIG. 3 is a front elevational view of the bus roof enclosure system of FIG. 1.

FIG. 4 is a rear elevational view of the bus roof enclosure system of FIG. 1.

FIG. 5 is a top plan view of the bus roof enclosure system of FIG. 1; and,

FIG. 6 is a front perspective view of the bus roof enclosure system of FIG. 1 coupled to a bus.

In the drawings, the broken lines in FIG. 6 depict a bus and form no part of the claimed design.
